CENTRIFUGAL DRIER

Anton C. Schmelzer, Cleveland, Ohio

Application September 6, 1935, Serial No. 39,479

16 Claims. (Cl. 210—76)

This invention relates in general to centrifugal clothes rinsing and drying machines adapted to be attached and driven by domestic washing machines as a substitute for the usual wringer, and 5 its principal object is the provision of a machine of that type with simple and effective means for preventing water drained and/or thrown from the clothes basket reaching the bearings for the drive shaft, so as to permit of the use of ball or 10 roller bearings for the drive shaft, which latter supports the clothes basket.

Another object of the invention is the provision of a centrifugal clothes rinsing and drying machine with an extracting element or clothes basket of obtuse conical shape having peripherally arranged extracting means and centrally arranged drainage means in the bottom face of the basket, in combination with stationary means 15 axially aligned with and extended through the basket supporting drive shaft for guiding the water drained and discharged from the basket to and through the drive shaft, thus prohibiting discharged water from contacting and interfering with the bearings mounting the drive shaft.

25 A further object of the invention is the provision of special coupling and supporting means between the hollow rotary shaft of a clothes rinsing and drying machine and the clothes basket, the coupling and supporting means being so arranged as to permit of the discharge of water 30 drained and discharged from the clothes basket centrally through said coupling and supporting means to and through the hollow shaft to prohibit discharge water from interfering with the 35 bearings mounting the rotary shaft.

Still another object of the invention is the provision of a centrifugal clothes rinsing and drying machine, embodying a hollow shaft, with an extracting element or clothes basket, which 40 basket includes a reenforced side wall provided with means for carrying any overflow water together with the drained and extracted water to and through the hollow shaft to prohibit any water from interfering with the bearings mounting 45 the rotary hollow shaft.

A still further object of the invention is the provision of a machine of this character, which is simple in construction, thoroughly reliable and efficient in its purpose, strong, durable, compact, 50 readily assembled and comparatively inexpensive to manufacture and install.

With the foregoing and other objects in view, the invention consists in the features of construction, combination and arrangements of parts, as 55 will be hereinafter more specifically described in

detail and illustrated in the accompanying drawing, wherein is shown the preferred embodiment of the invention, but it is to be understood that changes, variations and modifications can be made as come properly within the scope of the 5 appended claims without departing from the spirit of the invention or sacrificing any of its advantages.

In the accompanying drawing I show a vertical fragmentary sectional view through a centrifugal 10 clothes rinsing and drying apparatus constructed in accordance with the invention.

Referring now to the drawing in detail, the apparatus constructed in accordance with the invention, that is the preferred form thereof, 15 comprises a centrifuge section A and a drive section B. The centrifuge section A rests with its outer tank 2 upon the recessed top 3 of the drive section B and is secured thereto in a manner hereinafter described. This tank 2 encircles 20 an obtuse cone-shaped, rotatably mounted clothes basket 4, which basket consists of an obtusely cone-shaped part 5, extended into and resting upon the bottom face 6 of a dish-shaped lower part 7. The part 5 has its lower end encircled by a flanged, inverted cone-shaped apron 8, resting against and seated upon the flanged circumferential side wall of the lower part 7, to align the circumferential flanges 9 and 10 on the upper part 5 and the apron 8 respectively, and 25 permit of rigidly securing these flanges 9 and 10 to each other by means of rivets 11. The upper end of the part 5 is reinforced by a flanged, corrugated and obtusely cone-shaped skirting 12, the inwardly extended corrugations 14 of which 30 are spaced from the top of the skirting and contact at spaced intervals with the wall 15 of the part 5. The arrangement described reinforces 35 the part 5 and provides a plurality of longitudinal channels 16, in open communication with an 40 upper horizontally arranged, ring-shaped channel 17, encircling the upper end of the part 5, and a lower ring-shaped chamber 18, formed between the wall 15 of the part 5 and its apron 8.

These channels 16 guide water overflowing 45 from the basket 4 into its ring-shaped channel 16 to the ring-shaped chamber 18, from where such water is discharged through a plurality of openings 17' in the bottom of chamber 18 to and through the discharge openings 19 of the basket 50 4, and then carried away together with the drain and discharge water of the basket as will be later described. The skirting 12 is supported by a circumferential lateral flange 20 at its bottom end, which flange rests upon the flange 9 of the 55

part 5 and is secured thereto by means of the rivets 11.

Water drained and discharged from the basket 4 through a central drain opening 21 and the discharge openings 19 is fed into a funnel-shaped stationary member 22, the side wall 23 of which extends upwardly close to the flange 9 of the bottom part 7 of the basket 4. This member 22 is threadedly connected at 24 to a supporting pipe 25, extended through a hollow drive shaft 26 and supported upon the housing of the drive section B as will be later described.

The housing of the drive section B comprises a cup-shaped base plate 27 and a recessed top or cover member 28, the downturned peripheral wall 29 of which is secured to the upturned flange 30 of the base plate 27. The top member 28 is supported on legs 31, extended into pockets 32 of said member and secured thereto by rivets 33. The housing rotatably mounts the hollow basket drive shaft 26, which carries and is coupled with the basket 4. Thus a tube 37, secured to the base plate 27 and partially enclosing the shaft 26, carries upper and lower bearings 38 and 39, which pivotally support the shaft 26. The upper end of this tube 37 projects through an opening 40 in the top member 28 and is secured to said top member by a flanged bracket 41 sleeved upon said tube and welded thereto, and the lower end of said tube projects through an opening 53 in a recessed portion 54 of the base plate 27 and is secured thereto by means of a bracket 42, welded to the tube 37 and bolted to the base plate 27 by means of screw bolts 43. The lower and upper bearings 39 and 38 at opposite ends of the tube 37, which are ball bearings, have their inner rings or races 44 and 45 secured to the hollow shaft 26 and a cone-shaped male adapter 46 respectively, which adapter is in turn fixed to the shaft 26, whereas the outer rings 47 and 48 of said bearings are rigidly mounted in a cup-shaped bracket 49, welded to the upper end of the tube 37, and in the lower widened end of the tube 37. The male adapter 46 seats and is coupled with the central perforated portion 47' of a second adapter 48', which adapter is coupled with the basket 4. The perforation 49' of the adapter 48' permits of the pipe 25 being freely extended into and through the shaft 26. Adapter 48' is provided with an external cone-shaped face 50, which face engages and is coupled with a flanged female adapter 51 on the basket 4. This female adapter 51 is attached to the flange 10 of the bottom part 7 of the basket by means of the rivets 11, previously referred to, so that the rivets 11 unite the flanges, of the parts 5 and 7, the flange of the apron 8 and a flange 52 at the upper end of the female adapter 51. The flanges 9, 10, 20 and 52 form a heavy stabilizing ring for the basket 4, which ring is arranged in a plane approximately extending through the center of gravity of the combined basket and adapters.

The lower end of the drive shaft 26 carries a small gear 55, which is rigidly secured to said shaft by means of a nut 56. This small gear meshes with a combined gear and friction disc 57 driven from a variable frictional speed mechanism presently described. The gear 57, which extends through a slot 58 in the wall 59 of the recessed portion 54 for engagement with the gear 55 is mounted for rotation upon a hollow shaft 60, fixed to the base plate 27 by a nut member 61.

The variable frictional speed mechanism is adapted to be connected to and driven from a

conventional wringer-type washing machine, not shown herein, but clearly illustrated and described in my co-pending application Ser. No. 688,513, filed September 7, 1933, or may be driven from any desired source of power, such as an electric motor. For such purpose the variable frictional drive mechanism includes a drive shaft 62, which shaft extends through and is rotatably mounted in a bearing housing 63, supported at its opposite ends adjacent one side of the tank 2, by means of a bracket 64 and the top member 28 of the drive section B. The upper end of the shaft 62 (not shown) may be connected to and driven from a washing machine as disclosed in the application previously referred to or may be coupled with any other source of rotary power, such as a motor etc.

The lower end of the drive shaft 62 slidably supports a disc-shaped friction driver 65, splined to said shaft and axially movable with respect thereto, to permit of a coil spring 66, bearing at its upper end against a flanged collar 67, fixed to the shaft 62 by means of a pin 68, to yieldingly and resiliently engage and contact with an intermediate friction wheel 69. The wheel 69 is freely rotatably and axially shiftably supported upon a substantially horizontally disposed tubing or rod 70, preferably in the manner described in my application Serial Number 730,120 filed June 11, 1934, and the rod 70 is vertically slidably mounted on hollow shaft 60 and a post 71, in turn rigidly secured to the base plate 27 by a nut 72, so as to permit of vertical adjustments of the axis of rotation of said intermediate friction wheel 69 in case of wear of its friction surface.

The intermediate friction wheel, when in its idling position rests upon and frictionally engages an idler disc 73, which disc is pivotally mounted upon a stud shaft 74. This shaft is rigidly secured to the base plate 27 by means of a nut 75.

Shifting of the friction wheel 69 toward left by means such as for example described in the above referred to applications causes frictional engagement of the friction wheel 69 with the upper face 76 of the combined gear and friction disc 57 and therewith rotation of the shaft 26, which shaft mounts and is coupled with the cone-shaped female adapter 51 of the basket 4 by means of the adapter 48 and the male adapter 46, as will readily be seen from an inspection of the drawing.

The perforations 19 and 21 in the bottom face of basket 4 permit of drainage and discharge of water from the basket 4 prior to and during its rotation, so as to dispose of undesired surplus water from wet clothes dropped into the basket for drying purposes and to permit of discharge of the extracted water. Such water is then caught in the funnel-shaped stationary member 22 and hence guided through the pipe 25, extended through the hollow shaft 26, to the inlet 60 of a pump 77. To that end the pipe 25, which is extended through the hollow shaft 26 in slightly spaced relation from the inner wall thereof is rigidly supported by and seated within a tubular extension 78 of a cover plate 79, which is bolted to the base plate 27 of the drive section B by means of bolts 80. The tubular extension 78 is secured to the inlet of the pump 77 in any suitable manner, and the pump in turn is suspended from the base plate 27 by means of its flange 81, bolted to the base plate in alignment with a drain pipe 82 by means of bolts 83. The drain pipe 82 fully extends through the cover plate 28 of the drive section B and through a drain opening 84 into the tank 2 and is rigidly secured thereto by

means of a collar 85, cooperating with a shoulder 86 on the drain pipe in tightly sealing the tank 2, the top member 28 and the drain pipe 82 with respect to each other.

5 The pump 77 consists of a two part casing 87 in which a shaft 88, carrying impeller blades 89 is adapted to be rotated by means of a bevel gear drive 90, which in turn is driven from the friction driver 65 as will be presently described. 10 Thus the friction driver 65 carries at its circumferential surface gear teeth 91, meshing with a small gear 92 at the upper end of a freely rotatably mounted vertical shaft 93. This shaft extends through the hollow shaft 60 and is mounted 15 near its opposite ends in upper and lower ball bearings 94 and 95. A bracket member 96, rigidly attached to the tube 37, supports the upper ball bearing 94, while the lower ball bearing 95 is carried and supported by a gear casing 97, secured to the base plate 27 by means of bolts 98. The shaft 93, which extends into the gear case 97, carries at its lower end a bevel gear 99, meshing with a second bevel gear 100 within the gear case 97. The bevel gear 100 is attached to 20 the end of a shaft 101, which shaft carries at its opposite end a bevel gear 102, meshing with a bevel gear 103 at the lower end of the pump shaft 88. The bevel gears 102 and 103 are mounted in a gear casing 104 secured to the pump casing 87 by means of bolts 105. Preferably the two gear casings 97 and 104 are rigidly connected by means of a steel tubing 106 in order to form a more rigid driving connection between the pump shaft 88 and the shaft 93.

35 When the rinsing and drying apparatus is operated the pump 77 is continuously running, that is the pump is actuated, either when the basket 4 is rotating or at rest. Consequently the drainage and discharge openings 19 and 21 in the basket will effect draining of the surplus water through the hollow shaft 26 as soon as some of the goods to be dried are placed into the basket. Rotation of the basket forces the water in the goods outwardly and downwardly to the discharge openings 19, through said openings into the funnel-shaped member 22, hence to and through pipe 25 into the pump 77 and finally either to the washing machine or a set tub, neither of which is shown, so that all danger of water and/or suds reaching the bearings is avoided. Retardation of the rotation of the basket by contacts with the water or suds extracted from the clothes is also avoided.

Having thus described my invention, what I claim is:

1. In a centrifugal drier a support, a tank having an apertured bottom mounted on said support, drive mechanism carried by said support including a hollow driven shaft extended into said tank through said apertured bottom, a basket having discharge openings mounted on said driven shaft for rotation therewith, and stationary means encircling said basket opposite the discharge openings thereof and including a tubular member extended through said shaft for guiding liquid discharged from said basket to and through said hollow shaft.

2. A centrifugal drier as described in claim 1, wherein the tubular member of said stationary member is spaced from the inner wall of said hollow driven shaft and secured at its lower end to said support to permit of free rotation of the basket and its supporting shaft.

3. A centrifugal drier comprising a housing, 75 drive mechanism in said housing including a

hollow driven shaft extended outwardly through the upper wall of said housing, a tank having an apertured bottom mounted on the top of said housing and encircling the extended end of said driven shaft, a basket having discharge openings mounted on said hollow driven shaft for rotation therewith, funnel-shaped means enclosing said basket opposite its discharge openings and tubular supporting means for said funnel-shaped means in communication therewith and extended 10 downwardly therefrom through said hollow driven shaft, said tubular means being supported upon the lower wall of said housing and being spaced from the inner wall of said hollow driven shaft to permit of free rotation of the basket and 15 its supporting shaft.

4. In a centrifugal drier a support, a tank having an apertured bottom mounted on said support, drive mechanism carried by said support including a hollow driven shaft extended 20 into said tank through said apertured bottom, a rotary basket having openings for draining and discharging liquid therefrom, means for coupling said basket with said hollow shaft and supporting said basket thereon, and stationary liquid gathering and guiding means between said basket and said coupling means and extended into and through said hollow shaft for gathering and 25 guiding discharged liquid from said basket to and through said hollow shaft.

5. A centrifugal drier comprising a housing having a top and bottom portion, drive mechanism in said housing including a hollow drive shaft extended outwardly through the wall of the top portion of said housing, a tank having an 30 apertured bottom mounted on the top portion of said housing and encircling the extended end of said drive shaft, an obtusely cone-shaped basket having peripherally arranged discharge openings at the bottom thereof, means for coupling 35 said drive shaft and said basket including a male adapter supported by and connected with said drive shaft and a female adapter encircling the lower portion of said basket and secured thereto above said discharge openings, and stationary 40 liquid gathering and guiding means arranged between said basket and the said female adapter and in communication with said hollow drive shaft to permit of the liquid discharged from said basket being guided to and through said hollow 45 shaft.

6. In a centrifugal drier comprising a drive section and a centrifugal section an obtusely cone-shaped basket rotatably supported within said centrifugal section, said basket embodying 55 an obtusely cone-shaped upper portion provided with an integral skirting means encircling the lower part of said upper portion and a dish-shaped perforated bottom portion having said upper portion extending thereto, the side wall 60 of said dish-shaped portion encircling said skirting means and being attached thereto.

7. In a centrifugal drier comprising a drive section and a centrifuge section supported there- 65 by an obtusely cone-shaped basket rotatably supported within said centrifuge section, said basket embodying an obtusely cone-shaped upper portion, a skirting means for the lower part of said upper portion, and a dish-shaped bottom portion connected to the skirting means of said upper portion, the upper portion being extended into and seated with its lower edge upon said bottom portion, and said bottom portion being perforated adjacent to the lower edge of said upper portion to provide a plurality of discharge 70 75

openings at the lower peripheral edge of said basket.

8. In a centrifugal drier comprising a drive section and a centrifuge section an obtusely cone-shaped basket having its lower edge peripherally perforated, longitudinally corrugated reenforcement means encircling the upper part of said basket, and skirting means encircling the lower part of said basket, said reenforcement means and said skirting means embodying flanges oppositely arranged with respect to each other and rigidly secured together.

9. In a centrifugal drier an obtusely cone-shaped basket having its lower edge peripherally perforated, longitudinally corrugated reenforcement means encircling said basket and including an upper smooth wall portion spaced from the wall of said basket to form a ring-shaped overflow channel at the upper edge of said basket, and skirting means encircling the lower part of said basket in spaced relation with respect thereto, to form together with the wall of said basket a ring-shaped chamber encircling the lower part of said basket, said overflow channel and said ring-shaped chamber being in communication with each other through the longitudinal channels formed by the corrugations of said reenforcement means.

10. In a centrifugal drier a basket as described in claim 9, wherein said reenforcement means are formed at their lower edge with a circumferential flange, wherein said skirting means are formed at their upper edge with a circumferential flange opposite to and in alignment with respect to said flange on said reenforcement means, and wherein said two flanges are rigidly secured to each other.

11. In a centrifugal drier an obtusely cone-shaped basket having its lower edge peripherally perforated, longitudinally corrugated reenforcement means encircling the upper part of said basket and including an upper cone-shaped wall portion spaced from the wall of said basket for forming an overflow channel encircling the top of said basket, skirting means on the lower part of said basket encircling same in spaced relation with respect to the wall thereof to form a ring-shaped chamber encircling the bottom part of said basket, and circumferential, outwardly extending flanges on the bottom end of said reenforcement means and the top end of said skirting means, said flanges being arranged adjacent to and in alignment with each other and rigidly secured together, and said overflow channel and said ring-shaped chamber being in open communication with each other through the channels formed by the corrugations of said reenforcement means with the wall of said basket.

12. A centrifugal drier as described in claim 11, wherein said basket embodies an obtusely cone-shaped portion having its side wall at the lower end doubled back to form said skirting means, and a dish-shaped portion seating said cone-shaped portion and provided with a circumferential, flanged wall parallel to and contacting with said skirting means, said wall having its

flange connected to the flange of said reenforcement means and the flange of said skirting means and said flanges forming a stabilizing ring of substantial weight arranged a substantial distance above the bottom of said basket. 5

13. In a centrifugal drier a rotary basket having discharge openings, a ring-shaped open overflow channel on said basket encircling same, a ring-shaped chamber on said basket encircling same below said overflow channel, and a plurality of connecting passages between said overflow channel and said ring-shaped chamber to permit of free communication between said channel and said chamber. 10

14. In a centrifugal drier an obtusely cone-shaped, rotary basket having peripherally arranged discharge openings at its bottom, a ring-shaped, open overflow channel on said basket encircling same, a ring-shaped chamber on said basket encircling same below said overflow channel and provided with discharge openings, and communicating means between said overflow channel and said chamber to permit of liquid flowing from said overflow channel into said chamber, the discharge openings of said chamber being aligned with the discharge openings of said basket. 15 20 25

15. In a centrifugal drier a support, a tank having an apertured bottom mounted on said support, drive mechanism carried by said support including a hollow shaft extended into said tank through the apertured bottom thereof, a rotary basket having discharge openings coupled with and supported by said shaft, a ring-shaped open overflow channel on said basket encircling same, a ring-shaped chamber on said basket encircling same below said overflow channel and provided with discharge openings, communicating means between said channel and chamber, and stationary liquid gathering and guiding means encircling 30 35 40 said chamber and the basket opposite the discharge openings thereof, said liquid gathering and guiding means being extended into and through said hollow shaft for guiding liquid discharged from said basket and said chamber to 45 and through said shaft.

16. In a centrifugal drier a support, a tank having a centrally perforated bottom mounted on said support, drive mechanism carried by said support including a pump and a hollow shaft 50 extended into said tank through the central opening in the bottom thereof, a rotary basket having discharge openings coupled with and supported by said shaft, a ring-shaped open overflow channel on said basket encircling same, a ring-shaped chamber on said basket encircling same below said overflow channel and provided with discharge openings, communicating means between said channel and chamber, and stationary liquid gathering and guiding means encircling 55 said chamber and said basket opposite to said discharge openings thereof, said liquid gathering and guiding means being extended into and through said hollow shaft and in communication with said pump. 60 65
